UNITED STATES PATENT OFFICE.

JEREMIAH McGREVY, OF BROOKLYN, NEW YORK, ASSIGNOR TO SOLIDARITY WATCH CASE COMPANY, OF BROOKLYN, NEW YORK, A CORPORATION OF NEW YORK.

DESIGN FOR A WATCH-BOW.

53,078.

Specification for Design.

Patented Mar. 11, 1919.

Application filed February 18, 1918. Serial No. 218,012. Term of patent 14 years.

To all whom it may concern:

Be it known that I, JEREMIAH McGREVY, a citizen of the United States, residing at Brooklyn, in the county of Kings and State of New York, have invented a new, original, and ornamental Design for Watch-Bows, of which the following is a specification, reference being had to the accompanying drawing, forming part thereof.

Figure 1, is a front elevation of a watch bow showing my new design;

Fig. 2, is a cross section on the line 2—2 of Fig. 1.

I claim,—

The ornamental design for a watch bow, as shown.

JEREMIAH McGREVY.

Witnesses:

FRED HILLARD,
CHARLES P. COLE.
